CLAIM

(63) Continuation of application No. 29/136,031, filed on Jan. 22, 2001, now abandoned.

I claim the ornamental design for a combined ceiling rose, emergency light, alarm and detector, as shown and described herein.

(51) **LOC (7) Cl. 26-05**

DESCRIPTION

(52) **U.S. Cl. D26/72; D26/51**

FIG. 1 is a perspective view from above of a combined ceiling rose, emergency light, alarm and detector, showing my new design;

(58) **Field of Search** D26/51, 72-92; 362/147, 404-408, 432, 217, 223, 362

FIG. 2 is a perspective view of a component of FIG. 1, from below;

FIG. 3 is a perspective view of yet a further component of the combined ceiling rose, emergency light, alarm and detector shown in FIG. 1, from above; and,

FIG. 4 is a perspective view from above of a combined ceiling rose, emergency light, alarm and detector according to another embodiment of my new design, having a blank centre cap.

Components of the claimed article are shown separately for
